UNITED STATES PATENT OFFICE.

ANDREW FYRBERG, OF WORCESTER, MASSACHUSETTS.

TOP SNAP AND CYLINDER-CATCH FOR REVOLVING FIREARMS.

SPECIFICATION forming part of Letters Patent No. 735,490, dated August 4, 1903.

Application filed September 11, 1902. Serial No. 122,967. (No model.)

To all whom it may concern:

Be it known that I, ANDREW FYRBERG, a citizen of the United States, residing at Worcester, in the county of Worcester and State of Massachusetts, have invented a new and useful Top Snap and Cylinder-Catch for Revolving Firearms, of which the following is a specification.

This invention relates to that class of revolvers or other firearms in which the barrel is hinged to the fore part of the frame, so as to be thrown down when the firearm is to be opened.

The especial object of this invention is to provide a strong, simple, and inexpensive form of top snap for holding the barrel in its normal position and to combine the top snap with a simple, efficient, and inexpensive cylinder-catch for holding the cylinder in place, the top of the cylinder-catch being preferably located in position to form the tail sight, which is brought into line with the forward sight when the firearm is to be discharged.

To these ends this invention consists of the parts and combinations of parts, as herein-after described, and more particularly pointed out in the claim at the end of this specification.

In the accompanying drawings, Figure 1 is a side view of a revolver with this invention embodied therein. Fig. 2 is a fragmentary plan view showing parts of the pistol detached. Fig. 3 is a fragmentary side view, partially in section; and Fig. 4 is a bottom view of the top snap, showing the T-shaped spring therefor.

In a number of breakdown firearms the top snap which has been employed for holding the barrel in its normal position has been substantially T-shaped, so as to be adapted to engage the recess between posts which extend up from the frame. So long as the pivot of this form of top snap remains tight it will form an efficient construction; but when the pivot of the top snap is loosened it permits more or less side play to the end of the barrel, tending to render the construction shakily. In a firearm constructed according to this invention this difficulty is avoided by providing the barrel with a rigid tongue which fits down between the posts extending up from the frame, while the top snap is made in the form

of a U-shaped yoke, which straddles the posts or fits outside thereof, so that the tongue will keep the barrel in perfect alinement no matter how much the top snap wears or becomes loosened. The use of this form of top snap furthermore affords an opportunity to provide a cylinder-catch which is located in the tongue referred to and is so positioned that the head of the catch may serve as the tail sight of the firearm.

Referring to the drawings for a detail description of a firearm embodying this invention as shown in Fig. 1, A designates the frame of the firearm, B the barrel, pivoted at the forward end of the frame, and C the cylinder, which is connected to the barrel. These parts may be of the ordinary or approved construction and need not be herein described at length. Extending back from the barrel, as most clearly illustrated in Fig. 2, is a rigid tongue or part that is adapted to fit down between the posts 15, extending up from the frame A when the pistol is closed.

The top snap, as herein illustrated, consists of a substantially U-shaped frame 10, having knurled finger-pieces at its end, the arms of the U-shaped top snap 10 being pivoted on a screw 11. The U-shaped top snap 10 is adapted to straddle or extend outside of the posts 15 when the pistol is closed and serves to hold the parts in normal position in a simple and efficient manner. The spring which is used for operating the top snap is most clearly illustrated in Fig. 4. As shown in this figure, the arms of the U-shaped top snap 10 are notched, as at 12, to receive the ends of a T-shaped spring 13, the body portion of which is held in place by a screw 14.

The form of cylinder-catch preferably employed in connection with the U-shaped top snap consists, essentially, of a bell-crank-shaped catch 17, which is pivoted on a pin 19 in the tongue 16 and held in operative position by a small spring 18.

When it is desired to remove the cylinder for cleaning, reloading, or other purposes, the cylinder-catch 17 is moved back, so that the forward end thereof is lifted up out of the way of the cylinder, while said catch permits the cylinder to be pushed back into position and then snaps down behind the same to lock said cylinder in place. One particu-

lar advantage in the use of this form of cylinder-catch resides in the fact that the head of the cylinder-catch forms, in effect, a tail sight, which may be brought into alignment with the forward sight when the pistol is to be discharged.

I am aware that changes may be made in practicing my invention by those who are skilled in the art without departing from the scope thereof as expressed in the claim. For example, my invention may also be applied to a rifle or any other form of break-down firearm. I do not wish, therefore, to be limited to the construction I have herein shown and described; but

What I do claim, and desire to secure by Letters Patent of the United States, is—

In a revolving firearm, the combination of the framing, the barrel hinged thereto, a cylinder, a doubly-bolted locking mechanism for holding the barrel in its normal position, com-

prising two stationary bolts or projections on the framing, a rigid tongue extending back from the barrel to engage between said bolts, a substantially U-shaped locking-strap for engaging behind said bolts so that each of said bolts will be confined in a separate compartment or opening, a T-headed spring for holding the U-shaped strap in locked position, and a bell-crank-shaped cylinder-catch mounted in the rigid tongue entirely at the rear of the normal position of the cylinder and forming a ratchet-tooth which automatically engages behind the cylinder when the same is pushed into place.

In testimony whereof I have hereunto set my hand in the presence of two subscribing witnesses.

ANDREW FYRBERG.
